Primary Examiner — Sandra S Snapp*Assistant Examiner* — Leisha N Price(74) *Attorney, Agent, or Firm* — Bonini IP Law, LLC;
Frank J. Bonini, Jr.(57) **CLAIM**

The ornamental design for a fastener with cylindrical shank section, as shown and described.

DESCRIPTION

FIG. 1 is a top perspective view of a fastener with cylindrical shank section according to my new design;

FIG. 2 is a right side elevation view thereof;

FIG. 3 is a left side elevation view thereof;

FIG. 4 is a front elevation view thereof;

FIG. 5 is rear elevation view thereof;

FIG. 6 is a top plan view thereof; and,

FIG. 7 is a bottom plan view thereof.
